Primary Examiner — Paula Allen Greene(74) *Attorney, Agent, or Firm* — Altera Law Group, LLC(57) **CLAIM**

The ornamental design for a holder for a headset, as shown and described.

DESCRIPTION

FIG. 1 is a perspective view of an alternate embodiment of a cradle for an earpiece.

FIG. 2 is a right side view thereof.

FIG. 3 is a left side view thereof.

FIG. 4 is a front view thereof.

FIG. 5 is a back view thereof.

FIG. 6 is a top view thereof; and,

FIG. 7 is a bottom view thereof.

The broken lines depict environmental subject matter only and form no part of the claimed design.

1 Claim, 5 Drawing Sheets(56)
